US0D1044599S

(12) **United States Design Patent** (10) Patent No.: **US D1,044,599 S**
(45) Date of Patent: ** Oct. 1, 2024

(54) **PLANETARY ROVER**

(71) Applicant: **TOYOTA JIDOSHA KABUSHIKI KAISHA**, Toyota (JP)

(72) Inventors: **Koichiro Mizobuchi**, Susono (JP); **Mizuki Takehara**, Hachioji (JP)

(73) Assignee: **TOYOTA JIDOSHA KABUSHIKI KAISHA**, Toyota (JP)

(**) Term: **15 Years**

(21) Appl. No.: **29/847,824**

(22) Filed: **Jul. 28, 2022**

(30) **Foreign Application Priority Data**

Feb. 1, 2022 (JP) ..... 2022-001926 D

(57) **CLAIM**

The ornamental design for a planetary rover, as shown and described.

DESCRIPTION

FIG. 1 is a front, top and left side perspective view of a planetary rover showing our new design;

FIG. 2 is a front, top and right side perspective view thereof;

FIG. 3 is a front elevation view thereof;

FIG. 4 is a rear elevation view thereof;

FIG. 5 is a top plan view thereof;

FIG. 6 is a right side elevation view thereof; and,

FIG. 7 is a left side elevation view thereof.

The portions of the article shown in a light tonal contrast form no part of the claimed design.

1 Claim, 7 Drawing Sheets
